UNITED STATES PATENT OFFICE.

AUGUST ALVIN MONSON, OF MINNEAPOLIS, MINNESOTA.

SIGNALING APPARATUS FOR TELEPHONES.

No. 847,355.

Specification of Letters Patent. Patented March 19, 1907.

Application filed March 31, 1906. Serial No. 309,201.

To all whom it may concern:

Be it known that I, AUGUST ALVIN MONSON, a citizen of the United States, residing at Minneapolis, in the county of Hennepin 5 and State of Minnesota, have invented a new and useful Signaling Device for Telephones, of which the following is a specification.

This invention relates to telephone systems, and particularly to that class of systems wherein an automatic switchboard is employed at the central exchange to permit a subscriber at any substation to connect with any other substation without the intervention of an operator at the central station.

15 The principal object of the invention is to provide mechanism of simple construction to be employed at each substation for the purpose of making and breaking a selecting-circuit and sending to the central station a number 20 of impulses corresponding to the number of the station to be called.

A further object of the invention is to provide a calling device of the dial type, in which the dial or similar member is first 25 turned to adjust it in position to send the call and then is restored to its zero or normal position and during its return movement affects the making and breaking of the signaling-circuit, so that it is necessary for the subscriber 30 to restore the calling device to the zero or initial position before his call can be sent, as distinguished from other devices of the type where springs or the like are employed to return the calling mechanism to zero position.

35 A still further object of the invention is to provide a calling device of improved construction which is automatically locked and retained in position until released by the upward movement of the receiver-hook.

40 A still further object of the invention is to provide an improved calling device the position of which is adjusted to break a circuit automatically when the receiver is placed on the hook.

45 A still further object of the invention is to simplify, improve, and rearrange the circuits and circuit-closing devices to permit the closing of circuits through calling, ground, or talking wires.

With these and other objects in view, as will more fully hereinafter appear, the invention consists in certain novel features of construction and arrangement of parts, hereinafter 55 fully described, illustrated in the accompanying drawings, and particularly

pointed out in the appended claims, it being understood that various changes in the form, proportions, size, and minor details of the structure may be made without departing from the spirit or sacrificing any of the advantages of the invention.

In the accompanying drawings, Figure 1 is an elevation of a telephone switch-box provided with a calling mechanism constructed in accordance with the invention, the door of the box being shown in open position. Fig. 2 is a front view of the switch-box, a portion of the calling-disk being broken away in order to more clearly illustrate the construction. Fig. 3 is an elevation of the inner face of the door of the switch-box, the switch-box being shown in section. Fig. 4 is a vertical section through the door of the switch-box.

Similar numerals of reference are employed to indicate corresponding parts throughout the several figures of the drawings.

The switch-box, 10 of each substation is provided with a hinged door 11, which is shown in open position in order to more clearly illustrate the construction and arrangement of the circuits and circuit-controlling mechanism, and at the top of the switch-box are arranged three binding-posts 12, 13, and 14, the binding-post 12 being connected to a signaling-line 15, which runs to the central station, the binding-post 13 being connected to a grounded wire 16, and the binding-post 14 being connected to a wire 17, which leads to the central station and is termed the "talking-wire." The central portion of the door 11 is provided with an opening for the reception of a sleeve 19, within which is mounted a spindle 20, the shaft being arranged to rotate independently of said sleeve. To the outer end of the spindle is secured a calling-disk 21, having an operating-knob 22 for convenience in turning the disk first in one direction and then in the other direction to send the number of impulses necessary to connect the calling-station to the called station.

The periphery of this disk is graduated, and the graduations are provided with letters or numerals indicating the numbers of the several stations included in the system, and the disk in the present instance is shown as provided with twenty numerals, although the number may be increased or diminished.

The spindle 20 carries at one end a ratchet-wheel 24 and at the opposite end a circuit-closing disk 25. The ratchet-wheel fits with-

- in the dished portion of the disk 21 and is engaged by a pawl 26, carried by said disk 21, so that when the disk is turned to the right the pawl will click over the teeth of the ratchet-wheel without turning the latter; but when the disk is turned to the left the movement will be transmitted through the pawl to the ratchet-wheel and shaft 19, and the circuit-closing disk 25 will also be turned. The ratchet-wheel 24 is provided with teeth of a number corresponding to the number of graduations on the disk 21, and the circuit-closing disk 25 also has a corresponding number of teeth or shoulders 26', which may move into engagement with the end of a spring-contact 27 and force the same into engagement with a contact 27' for the purpose of closing the selecting-circuit. The springs 27 and 27' are carried by insulating-blocks 28, secured to the inner face of the door, and the free end of spring 27 is curved downward and normally lies in a space between two of the teeth 26, but out of contact with the disk 25, the selecting-circuit being normally broken. The downward movement of the contact 27 is limited by a stop-pin 29, that projects from the inner face of the door.

To the inner face of the door is secured a metallic plate 30, which serves as a reinforce or bearing member for the hollow sleeve 19. Leading from one of the door-hinges to the contact 27' is a wire 31, while the spring-contact 27 is connected to a wire 33, leading to a second hinge 34.

In operating this part of the mechanism the highest numeral 20 of the calling-dial normally stands in a position opposite an indicator or pointer *x*, and the spring-contact 27 is normally opposite one of the spaces between the teeth 26 of the selecting-disk. When a subscriber wishes to call a substation—for instance, substation 5—he grasps the knob 22 and turns the disk 21 to the right until the numeral 5 of the disk is opposite the indicator *x*. During this movement the pawl 26 clicks over the teeth of the ratchet-wheel 24, but the ratchet-wheel and the selecting-disk are held stationary by a locking-pawl 35, pivoted to the inner face of the door and under the control of the receiver-hook 36, which when depressed by the weight of the receiver *R* engages an arm 37, projecting from the pawl 35, and presses the toothed inner end of the pawl between two of the teeth of the selecting-disk. The subscriber then removes his receiver from the hook and the latter is elevated in the usual manner, and as the inner end of the locking-pawl 35 is much heavier than that end which engages the receiver-hook it will move by gravity from engagement with the selecting-disk, whereupon the subscriber turns the dial 21 to the left, and the pawl 26 engages the teeth of the ratchet-wheel 24, turning the latter, and the selecting-

disk 25 and the teeth 26' of said disk pass successively under the spring-contact 27, moving the latter into and out of engagement with the contact 27' and making and breaking the selecting-circuit five times, corresponding to the number of the station to be called, and at the completion of this movement the contact-spring 27 rests in contact with one of the teeth of the selecting-disk and with the upper contact 27' and remains in that position to hold the circuit closed until the conclusion of the conversation.

Projecting from the inner face of the selecting-disk is a crown ratchet-wheel 37, having teeth of a number corresponding to the number of teeth of the selecting-disk, and the teeth of this ratchet-wheel are arranged to be engaged by an arm 38, projecting upward from the receiver-hook 36, these parts being so proportioned and arranged that when the receiver is once more hung on the hook the arm 38 in moving downward will engage one of the teeth of the crown-ratchet 37 and will turn the selecting-disk for a distance equal to half the space between two adjacent teeth, this movement being sufficient to break the connection between the spring-contacts 27 and 27' and restore the parts to initial position with the selecting-circuit broken. In this connection it may be observed that it is necessary to send to the central station a number of electrical impulses corresponding to the number of the station to be called, and should the number of that station be greater than the highest number of the disk the disk may be turned more than a single revolution. For instance, if the station to be called is number 107, the calling-disk 21 will be turned to the left to the extent of five complete revolutions, and as each revolution of the disk means twenty makes and breaks, five revolutions would be equal to one hundred impulses sent over the selecting-line, and then the operator turns the disk to the right until the number "7" appears on the indicator *x* and then to the left until the highest number is again under the indicator *x*, so that one hundred and seven impulses are sent to central station, and substation 107 will be automatically connected by the mechanism at the central station.

At each of the substations is a transmitter *T*, an inductorium *I*, a call-bell *C*, and a relay 40, the latter being so connected in the line that when a calling-circuit is closed it will connect the call-bell with the local battery *B*, so that the bells of any station will ring no matter how remote it may be from the central station.

Within the switch-box are arranged two blocks 41 and 42, formed of insulating material and carrying circuit-closing strips 43 and 44, that are insulated from each other. The lower end of the strip 44 is arranged in the path of movement of an upwardly-bent arm

45, that is carried by the inner end of the switch-hook 36, so that when the receiver is on the hook this arm engages the contact 44 and holds it out of engagement with a contact 46, that is secured within the switch-box. When the receiver is removed from the hook, the arm 45 descends and the contact 44 is allowed to engage contact 46. This contact 44 is connected by a wire 48 with the hinge 32, and the contact 46 is connected by a wire 49 to the ground binding-post 13. The contact 43 normally engages a stationary contact 50, that is secured within the switch-box, and said contact 43 is connected by a wire 51 to the relay-magnets 40, the wire being thence continued to the binding-post 14 of the talking-wire. At one side of the telephone-box is a push-button 52, extending through an opening in the side wall of the box and arranged to engage the contact 43 and press the same into engagement with the contact 44, and as a result of this contact 43 is moved out of engagement with contact 50 and contact 44 is moved out of engagement with the contact 46.

Arranged below the receiver-hook 36 are four spring-contacts 55 56 57 58, the free end of the contact 57 being bent upward and being engaged by the receiver-hook when the latter is depressed by the weight of the receiver, and when the receiver-hook is down the contact 57 is forced into engagement with the contact 58, while the contacts 55 and 56 are wholly disconnected.

Tracing now the selecting-circuit from ground at the substation to wire 16, binding-post 13, wire 49, contact 46, (receiver removed from hook,) contact 44, wire 48, hinge 32, wire 31, spring-contact 27, contact 27, wire 33, hinge 34, wire 60, binding-post 12, wire 15, central station, and at the central station through the automatic selecting mechanism and a battery to ground. The selecting impulses having been sent and the spring 27 being allowed to remain on one of the teeth 26' of the selecting-disk, the subscriber at the calling-station depresses the button 52 and forces the contact 43 into engagement with the contact 44, thus moving contact 43 from contact 50 and contact 44 from contact 46. This completes a circuit from the battery and signaling mechanism at central through wire 15, binding-post 12, wire 60, hinge 34, wire 33, contact 27, spring-contact 27', wire 31, hinge 32, wire 48, contact 44, contact 43, wire 51, the electromagnets of relay 40, and out through binding-post 14 and the talking-wire 17 back to the central station, and from thence, as will be hereinafter described, through the similar circuits of the called subscriber in order to energize the relay-magnets 40 at both the calling and the called stations.

When the relay-magnets are energized, 65 each magnet attracts its armature 61, and

the armature-lever 62 moves over against the contact 63 that is carried by the casing, and this closes a local circuit through the call-bell C, which may be traced from the battery B through wire 65, contact 63, armature-lever 62, wire 66, the electromagnets of the call-bell, and call-bell frame to wire 67 back to battery, and this system is followed in each of the substations, so that no matter how remote the station may be from central 75 the call-bell will be sounded with sufficient distinctness to be heard. After pressing the button if the call-bell of the calling-station is sounded the subscriber knows that the call-bell of the called station has also sounded 80 and that he is connected; but if the bell fails to sound he is informed that the line is busy and that he cannot connect at that time.

In following the talking-circuit from the talking-wire 17 it will be seen that the current will flow through binding-post 14, wire 51, and the relay-magnets to the spring-contact 48, contact 50, wire 70 to the secondary of the inductorium, wire 71, receiver R, wire 72, contact 55, contacts 56 57, wire 73, contact 46, wire 49, binding-post 13, and to ground by wire 16, the connections at the other substation being completed in a similar manner.

The primary circuit may be traced from 95 battery B through wire 80, transmitter T, thence by wire 81 to the primary of the inductorium, wire 72, contact 55, (receiver-hook elevated,) contact 56, wire 82 to battery. When the receiver-hook is down, contacts 55 and 56 are disconnected and the primary circuit is broken.

When the receiver-hook is down, the line is open to receive a calling-signal from the talking-wire 17, binding-post 14, wire 51, the electromagnet 40 of the relay, contact 43, wire 85, contact 58, contact 57, wire 73, contact 46, wire 49, binding-post 13, and wire 16 to ground.

I claim:

1. In selective calling and signaling apparatus, a revoluble circuit-closing disk having a plurality of spaced circuit-closing means, a receiver-hook, a receiver-hook-controlled locking means for holding said disk from movement in either direction while the receiver-hook is down, a manually-operable means for turning the disk to effect make and break of the calling-circuit, said disk being movable at the completion of a calling operation 115 to maintain the circuit closed, and means under the control of the receiver-hook for moving said disk to break circuit when the receiver is placed on the hook.

2. In telephony, a substation calling and selecting device, including a revoluble disk, having a notched periphery, a pair of contacts under the control of said disk, said disk being manually adjustable to remain at the end of a calling operation in circuit-closing 130

position, and a receiver - hook - controlled means for moving said disk to break circuit when said receiver-hook is depressed.

3. In telephony, a substation calling and signaling mechanism comprising a revolute disk having a notched periphery, a pair of spring-contacts, one of which is adapted for engagement with the periphery of the disk, means for limiting the movement of said contact in the direction of the disk, said disk being manually adjustable to remain in circuit-closing position at the end of the calling operation, and a receiver-hook-controlled means for moving the disk to break circuit.

4. In telephony, a substation calling and signaling means comprising a revolute disk having a notched periphery, a spring-contact member arranged to engage the periphery of the disk, a stop-pin for limiting the movement of said member in the direction of the disk, a crown ratchet-wheel on one face of the disk, a receiver-hook, and an arm carried by the receiver-hook and arranged to engage said crown ratchet-wheel.

5. In telephony, a substation calling and signaling means, comprising a revolute disk, a receiver, a receiver-hook, a disk-locking device movable into engagement with the disk when the receiver is placed on the hook, a crown ratchet-wheel on one face of the disk, and an arm carried by the receiver-hook and arranged to engage said ratchet-wheel.

6. In telephony, a substation calling and signaling device, comprising a revolute disk having a notched periphery, a locking-lever having one end arranged to engage the disk and provided at its opposite end with a projecting arm, and a receiver-hook arranged to engage said arm when depressed and lock said disk from movement.

In testimony that I claim the foregoing as my own I have hereto affixed my signature in the presence of two witnesses.

AUGUST ALVIN MONSON,

Witnesses.
